CONTACT CONSTRUCTION

Stephan Miller, Wilkinsburg, and Peter A. Pontius, East Pittsburgh, Pa., assignors to Westinghouse Electric Corporation, East Pittsburgh, Pa., a corporation of Pennsylvania

Application May 29, 1943, Serial No. 488,980

1 Claim. (Cl. 173—324)

1

This invention relates, in general, to electrical contact structures, and more specifically to resilient contact structures. There are many applications where electrical contact structures having resilient characteristics are required. In many of these applications, the contacts are subjected to alternate heating and cooling, and it is necessary that the resilient characteristics of the contact remain unimpaired under such conditions in order that adequate contact pressure be assured at all times.

In the past, the problem has been solved by adding spring reinforcing members to brace contacts of a non-resilient material, such as copper. Such reinforcing members comprise extra parts added to conventional contacts and materially increased the complexity and cost of the contacts. Another approach to this problem has been the use of copper alloys as contact materials. This, however, involves the use of relatively rare metals, and also increases the cost.

One object of this invention is to provide a novel resilient contact construction which is efficient in operation yet economical of manufacture.

A more specific object of the invention is to provide a novel contact structure comprising a core of resilient material at least the major portion of which is clad with a good electrical conducting material.

Another object of this invention is to provide a novel contact construction embodying a core of a material capable of heat treatment to obtain resilient properties, with at least the major portion of the core clad with a good electrical conducting material.

Another object of this invention is to provide a novel contact structure comprising a core of resilient material clad with a good electrical conducting material, and having on at least the contacting portion thereof a layer of a noble metal.

Another object of this invention is to provide a novel contact structure bent to shape from composite strip material which is capable of heat treatment after bending to obtain resilient properties.

These and other objects of this invention will become more apparent upon consideration of the following detailed description of preferred embodiments thereof, when taken in connection with the attached drawing, in which:

Figure 1 is a side elevation view of a fuse mounting having contact clips constructed in accordance with this invention;

Fig. 2 is a side elevation view of a combined fuse and disconnect switch mounting having con-

tact clips constructed in accordance with this invention;

Fig. 3 is a section through one contact clip shown in Fig. 1, and taken substantially along the line III—III thereof;

Fig. 4 is a section through a contact clip taken substantially on the line IV—IV of Fig. 2;

Fig. 5 is an enlarged transverse section taken through one leg of the clip shown in Fig. 4 substantially on the line V—V thereof;

Fig. 6 is an enlarged transverse section taken through one leg of the clip shown in Fig. 3 substantially on the line VI—VI thereof;

Fig. 7 is an enlarged transverse section through one leg of the clip of Fig. 3 taken substantially on the line VII—VII of Fig. 3;

Fig. 8 is a section of a clip similar to Fig. 4, but illustrating a modified form; and

Fig. 9 is an enlarged transverse section taken through one leg of the clip shown in Fig. 8.

The contact constructions constituting this invention may be embodied in various types of electrical apparatus wherein resilient contacts are required. The invention is illustrated in the drawing as embodied in contact clips which must have resilient characteristics in order to provide an adequate contact pressure when a cooperating contact is inserted in the clip.

In Fig. 1, there is illustrated contact clips constructed in accordance with this invention for cooperation with a fuse. The fuse is preferably mounted on a base 2 of insulating material, such as porcelain or a molded insulating material. Generally U-shaped contact clips 4 and 5 are supported on the base and secured thereto by bolts 6 extending through apertures provided in the bight portions of the clips, respectively, and through apertures in base 2.

In accordance with this invention, the contact clips 4 and 5 are preferably made by cutting strips of suitable length from composite strips, straps, flat rectangular wires or the like. These composite strips or the like comprise a central layer or lamination 8 of a resilient material, preferably a material such as carbon steel which is responsive to heat treatment to acquire increased spring characteristics. The central layer 8 is clad with a relatively good electrical conducting material 10, such as copper, brass, silver, or the like.

Any desired method may be employed for securing the layers 8 and 10 together. One method which may be employed comprises supporting a steel billet in a mold and pouring the molten copper or other good electrical conducting material around the steel billet to completely enclose the

billet. After this has cooled, it may be rolled to any desired length or thickness so that a strip or the like from which fuse clips may be made will be provided completely clad with copper or similar material, as shown for example in Fig. 7. This method will be hereinafter referred to as the casting method.

Another method for making the strips from which fuse clips may be cut, is to apply the strips of copper or other good conducting material to opposite sides of a steel billet, sheet or the like, and roll the resulting sandwich-like structure at a predetermined high temperature to cause the outer and inner layers to become intimately bonded together. Such a structure may then be rolled to the desired thickness, and the strip of material produced will be substantially as shown in Fig. 5, that is, the central steel layer will be provided with good conducting material 10 only on opposite sides thereof, with the edges of the steel layer exposed. This method of making strips from which fuse clips may be cut will be hereinafter referred to as the rolling method.

When strips are cut from a strip or the like formed in accordance with the casting method, they may be further cut along one edge to provide integral tabs 12 which may then be bent inwardly towards each other to form stops. During the cutting operation, the contact clip blanks may also be cut to form an integral terminal 14 which extends laterally from the bight portion of the clip. The contact clip 4 shown in Figs. 1, 3, 6 and 7 is bent to shape from material formed by the casting method. It will be noted that this clip has conducting material 10 covering the major portion of central layer 8, but has the central layer or core 8 exposed at the outer end edges of the leg portions of the clip, and at one side edge, except for the space occupied by stops 12. This clip has the leg portions thereof formed with outwardly curved intermediate portions for receiving terminal ferrules 16 on a fuse 18. Stops 12 formed on clips 4 and 5 are for the purpose of preventing longitudinal movement of the fuse relative to the clips.

After the contact clip has been bent to shape, such for example as the shape illustrated in Fig. 3, the clip may then be subjected to heat treatment to harden the steel core 8 and increase the resiliency thereof. Such a treatment, while hardening the steel and increasing its resilient characteristic, may or may not have this effect on the outer layers 10 depending upon the material used. Thus, relatively pure copper does not have any resilient properties imparted to it by heat treatment but the conductivity thereof is increased by such treatment. Certain copper alloys, however, such as beryllium copper, do have their resilient properties increased by heat treatment.

Four contact clips 20, 22, 24 and 26 are illustrated in Fig. 2 as being supported on a base 21 of insulating material, in the same manner as contact clips 4 and 5 are supported on the base 2 of Fig. 1. The two intermediate contact clips 24 and 26 are shown as having an integral common base 25. The clips supported on base 21 are formed with leg portions having flat parallel intermediate portions terminating in flared outer ends for cooperation with the knife blade terminals 28 of a fuse 30, and for receiving a disconnecting switch blade 32. The disconnecting switch blade 32 may be pivoted on clip 24, as by a pivot 34, for movement of the other end thereof into and out of engagement with contact clip 20.

5 Contact clips 20, 22, 24 and 26 may be formed by cutting strips from a composite bar made by the rolling process as illustrated in Fig. 5. Such a clip will have layers of good conducting material 10 only on opposite sides thereof, as illustrated. However, these clips will have the major portion of central layers 8 clad by conducting material 10, because only the side and end edges of the central layer will be exposed.

10 A contact clip cut from material formed by either the casting or the rolling method, may have an added layer 36 applied thereto of a noble metal such as silver, gold, platinum or the like. Figs. 8 and 9 illustrate a contact clip like that shown in Fig. 4 having an added coating 36. Where silver is utilized for the material for coating 36, it is preferably electrolytically applied so as to completely enclose central layer 8 to protect it from corrosion. Layer 36 also serves the purpose of improving the contact surface, and providing a complete jacket for layers 8 and 10 of good conducting material, thereby increasing the conductivity of the clip and decreasing the electrical contact resistance of the clip.

15 Contact constructions such as those described above have a relatively high electrical conductivity, and also have very good resilient characteristics, and these results are obtained by the economical use of relatively common materials. Thus, steel which is a relatively cheap and abundant material constitutes the main portion of the contact, and only a relatively small amount of copper or other good electrical conducting material need be employed, as compared to contacts constructed entirely of copper, or similar material, or alloys thereof. Moreover, by covering substantially the entire surface of central layer 8, the steel is protected from corrosion, and by using a protective layer of relatively good electrical conducting material, low contact resistance is obtained and the conductivity of the clip is materially increased. As pointed out above, the outer layer 10 of good electrical conducting material may cover the entire surface of central layer 8, in which case even better protection of the central layer is obtained, together with increased conductivity. By providing a covering of good electrical conducting material, at least on opposite sides of the central layer 8, a terminal may be formed integral with the contact, or may be secured to either side thereof in engagement with either layer 10 of good electrical conducting material. It is believed apparent that with a contact clip constructed in accordance with this invention, no supplemental reinforcing means is necessary as with solid copper clips, because of the high resiliency of central layer 8. Obviously, less copper is required than with solid copper clips or clips of a copper alloy. Furthermore, contacts constructed in accordance with this invention may be first bent to shape, after which they may be heat-treated to impart additional resiliency to the central layer 8.

20 Having described preferred embodiments of the invention in accordance with the patent statutes, it is desired that the invention be not limited to these particular embodiments inasmuch as it will be obvious to persons skilled in the art that many modifications and changes may be made in these particular embodiments without departing from the broad spirit and scope of this invention.

25 We claim as our invention:

An elongated resilient contact member constructed to engage a cooperating contact member at one point and to have an electric conductor

secured thereto at a remote point, comprising, an elongated carbon steel leaf spring having relatively high electrical resistance, said spring being clad with a resilient beryllium copper alloy in a continuous layer connecting said points.
